HARRY E. MCCOY.
BY MARTIN P. SMITH, ATTY.

UNITED STATES PATENT OFFICE

2,094,803

PLAYING CARD SHUFFLING DEVICE

Harry E. McCoy, Los Angeles, Calif., assignor, by
mesne assignments, to Jeannette Northrup,
Los Angeles, Calif.

Application August 14, 1935, Serial No. 36,074

13 Claims. (Cl. 273—149)

My invention relates to a playing card shuffling device and has for its principal object, the provision of a relatively simple, practical and inexpensive device that may be conveniently employed for the comparatively rapid and effective shuffling of playing cards.

A further object of my invention is, to provide a card shuffling device having relatively few operating parts, thus minimizing the possibility of failure of the device to function properly after having been set and released.

A further object of my invention is, to provide a card shuffling device having a rotating member that serves as a support for the unshuffled pack of cards when said pack is inserted in the device and said member being constructed so that when it moves away or out of card supporting position, it separates the pack of cards into two or more parts and then releases the cards one at a time from each of the separated parts, thereby effecting a very thorough and complete shuffling of the cards.

A further object of my invention is, to provide simple and efficient means whereby the speed of the device in accomplishing the card shuffling operation, may be very accurately regulated and controlled.

With the foregoing and other objects in view my invention consists in certain novel features of construction and arrangements of parts that will be hereinafter more fully described and claimed and illustrated in the accompanying drawing in which:

Fig. 1 is a front elevational view of a card shuffling device constructed in accordance with my invention.

Fig. 2 is a front elevational view of the card magazine and shuffling means removed from the case or housing.

Fig. 3 is an enlarged vertical section taken on the line 3—3 of Fig. 1.

Fig. 4 is a vertical section taken approximately on the line 4—4 of Fig. 3, with the magazine removed from its case or housing.

Fig. 5 is an enlarged vertical section taken on the line 5—5 of Fig. 1.

Fig. 6 is an enlarged vertical section taken on the line 6—6 of Fig. 2.

Fig. 7 is a plan view of the card supporting and shuffling member and showing a portion of a pack of cards supported thereon.

Fig. 8 is an enlarged plan view of the end of the card supporting and shuffling member and showing the same provided with two projecting members.

Fig. 9 is a cross section taken on the line 9—9 of Fig. 8.

Fig. 10 is a plan view of the end of the card supporting and shuffling member and of the type having a single projecting member.

Fig. 11 is a vertical section taken through the center of the card supporting and shuffling member and showing the same in card supporting position.

Referring by numerals to the accompanying drawing which illustrates a preferred embodiment of my invention, 10 designates a substantially rectangular cover or housing that encloses the operating parts of the device and which cover may be formed of sheet metal, celluloid or the like and designed and suitably decorated so as to present a neat and finished appearance.

Formed in the lower portion of the front wall of the housing, is an opening 11, through which the pack of cards may be conveniently withdrawn after having been shuffled.

Housing 10 is removably positioned on a base 12 and secured to said base and enclosed by said housing is the magazine that receives and holds the pack of cards to be shuffled. This magazine comprises a rear wall 13, a front wall 14 and end walls 15.

The chamber 16 within the upper portion of this magazine is adapted to receive the pack of cards to be shuffled and the chamber 17 in the lower portion constitutes a pocket that receives the shuffled cards.

The lower portions of the front and rear walls of the magazine are disposed so that the pocket 17 is substantially V-shape in cross section in order that the pack of shuffled cards when positioned in said pocket, will occupy an inclined position as illustrated by dotted lines in Fig. 5, with the upper end of the pack positioned in the opening 11 in the front wall of the housing.

An opening 18 is formed in the lower portion of the front wall 14 of the magazine in order to permit the convenient engagement of the upper portion of the pack of shuffled cards between the thumb and fingers when the shuffled pack is removed from the device.

A portion 20 of the rear wall 13 of the magazine is extended forwardly in order to provide a deflector that causes the cards to be directed forwardly as they drop in succession into the 50 pocket 17.

The upper ends of the surrounding rear and end walls of the magazine are bent or curved slightly outward as designated by 21, in order to facilitate the insertion of the pack of cards into 55

the chamber 16 in the upper portion of the magazine.

Formed in one of the end walls of the magazine, preferably the one on the lefthand side thereof, is an opening 22 between the chambers 16 and 17 and secured to and projecting outwardly from this side wall to the sides of said opening, are bearings 23 for a horizontally disposed shaft 24. This shaft projects through an opening of the front wall of housing 10 and mounted on the front wall of said shaft, is a small knob or disc 25.

Mounted on shaft 24 between the bearings 23, is a combined card supporting and shuffling member which in the present instance, consists of an arcuate plate 27 or a body having a curved peripheral surface that is preferably concentric with the axis of shaft 24.

The forward portion of this card supporting and shuffling member is slotted as designated by 28 to form two or more forwardly projecting members 29 and which latter preferably taper in width toward their forward ends.

Formed on the side edges of plate or body 27, are marginal ribs 30 that are preferably of inverted V-shape in cross section and these ribs are extended along the side edges of the tapered projections 29, as designated by 31.

In some instances it may be found desirable to eliminate the ribs 31 on the sides of the projections 29 and if desired one of the projections may be made slightly longer than the other so as to effect a more thorough shuffling of the cards.

35 In Fig. 7 I have shown the combined card supporting and shuffling member 27 provided on the rear portions of its side edges with substantially inverted V-shaped ribs 32, which gradually diverge as they approach the forward slotted portion of said member and formed on the curved surface of member 27 between the diverging forward ends of ribs 32, is a short circumferentially disposed rib 33 that gradually decreases in width toward both of its ends.

45 The forward end of this rib 33 terminates at the inner end of the central one of a plurality of slots or notches 34 that are formed in the forward end of member 27 and this rib 33 separates the pack of cards that is supported by member 27 and the two parts of said member are withdrawn from beneath the supported pack of cards.

Formed on the forward portion of the surface of member 27 to the sides of the forward end of rib 33, are short ribs 35, the forward ends of which terminate at the inner ends of the corresponding slots or notches 34 and these ribs are effective in dividing the two parts of the pack that were divided or separated by rib 33 and thus the complete pack of cards is divided into four parts or sections before the cards begin to drop off the edges of the projections 36 that are formed by the slotting of the forward end of member 27.

65 The projections 36 are preferably tapered toward their forward ends and as a result of the construction just described, the cards will drop off the supporting member at eight different points or from both edges of each projecting member 36. If desired the side edges of the members 36 may be provided with small upwardly projecting ribs 37 that are substantially of inverted V-shape in cross section.

In Fig. 10 I have illustrated the forward portion of the card supporting and shuffling mem-

ber 27 provided with a single tapered projection 38, the side edges of which may be provided with small inverted V-shaped ribs 39 and extending longitudinally on the surface of the projecting member 38, is a longitudinally disposed groove 40 of sufficient width to accommodate one or more playing cards.

Pivottally connected in any suitable manner to the rear portion of member 27, is the upper end of a depending rod 41, the lower portion of which carries a piston 42 that is arranged for operation within a cylinder 43.

Formed in the bottom of cylinder 43, is a vent 44 and the flow of air through this vent is controlled by screw 45 that is seated in the bottom 15 of the cylinder.

Projecting laterally from the intermediate portion of rod 41, is an arm 50 to which is connected the upper end of a retractile spring 51 and the lower end of this spring is connected to base 12. 20

The operation of the card shuffling device is as follows:

Before placing the pack of cards to be shuffled in the device, disc or knob 25 is engaged and shaft 24 is rotated clockwise, thereby moving the 25 card supporting and shuffling member 27 through opening 22 into the lower portion of chamber 16. Such action moves piston 42 upward within its cylinder 43 and expands spring 51, thereby re-30 storing power therein.

As member 27 is thus swung into the chamber 16, the point of pivotal connection between rod 41 and member 27 will move past center, that is, it will move a slight distance beyond the vertical plane occupied by the axis of shaft 24 and when such action occurs, the member 27 will be restrained against rearward movement as a result of the pull exerted by spring 51.

The pack of cards to be shuffled is now inserted into chamber 16 with one of the lower corners of said pack resting on the periphery of member 27.

Knob or disc 25 is now engaged and rotated a slight distance anticlockwise to bring the point of pivotal connection between rod 41 and member 27 past center, whereupon knob 25 is now released and spring 51 will now act to draw rod 41 downward and which movement imparts rotary movement to the card supporting member 27.

The flow of air from the chamber in cylinder 43 below the piston 42 therein through vent 44, controls the speed of downward movement of said piston and the rod 41 and this speed control may be very accurately regulated by adjusting screw 45 so as to increase or decrease the size 55 of the vent.

As member 27 is slowly rotated back to its normal position, the cards supported by said member will ride over the periphery of said member and finally said cards will engage and ride over the ribs on the edges of the tapered projections on the forward end of said member and said cards will discharge or drop off the inclined side edges of said members at two or more different points and which action is very effective 65 in shuffling the pack of cards.

As the cards drop from the projections on the forward end of the supporting and shuffling member they will pass downwardly into pocket 17 and in striking against the inclined portion 70 of rear wall 13, said cards will be deflected forwardly and pile one on top of the other in the pocket 17.

Among the especially advantageous features of my invention are, the card supporting and shuf- 75

filing member which when moved into the magazine, provides a support for the pack of cards to be shuffled, which member when withdrawn from the magazine automatically divides the pack of cards into two or more parts, each containing approximately the same number of cards and the cards finally dropping off the support at two or more different points so as to effect a very thorough shuffling of the cards, also the means for controlling the speed of withdrawal movement of the card supporting and shuffling member and which speed regulating means may be very accurately controlled.

Thus it will be seen that I have provided a card shuffling device that is relatively simple in construction, inexpensive of manufacture and very effective in performing the functions for which it is intended.

It will be understood that various changes in the size, form and construction of the different parts of the playing card shuffling device herein set forth may be made and substituted for those herein shown and described without departing from the spirit of my invention, the scope of which is set forth in the appended claims.

I claim as my invention:

1. In a card shuffling device, a card-receiving magazine, a member mounted for rotation on the side of said magazine and adapted when rotated to move into or out of said magazine, and that portion of said rotatable member that enters the magazine having a longitudinally curved peripheral card-supporting surface.

2. In a card shuffling device, a card-receiving magazine, a member mounted for rotation on the side of said magazine and adapted when rotated to move into or out of said magazine, that portion of said rotatable member that enters the magazine having a longitudinally curved peripheral card-supporting surface and automatically operating means connected to said rotary member for imparting rotary movement thereto, so as to withdraw said member from the magazine and release the supported cards.

3. In a card shuffling device, a card-receiving magazine, a member mounted for rotation on the side of said magazine and adapted when rotated to move into or out of said magazine, that portion of said rotatable member that enters the magazine having a longitudinally curved peripheral card-supporting surface, automatically operating means connected to said rotary member for imparting rotary movement thereto, so as to withdraw said member from the magazine and release the supported cards and means for regulating the speed of rotation imparted to said rotary member.

4. In a card shuffling device, a card-receiving magazine, a member mounted for rotation on the side of said magazine and adapted when rotated to move into or out of said magazine, that portion of said rotatable member that enters the magazine having a longitudinally curved card-supporting surface, automatically operating means connected to said rotary member for imparting rotary movement thereto, so as to withdraw said member from the magazine and release the supported cards and manually operable means for rotating said member so as to move the portion having the curved card-supporting surface thereinto of the magazine.

5. In a card shuffling device, a card-receiving magazine, a member mounted for rotation on the side of said magazine and adapted when rotated to move into or out of said magazine, that portion of said rotatable member that enters the

magazine having a longitudinally curved card-supporting surface and longitudinally curved fingers projecting from the end of said curved peripheral card-supporting surface.

6. In a card shuffling device, a card-receiving magazine, a member mounted for rotation on the side of said magazine and adapted when rotated to move into or out of said magazine, that portion of said rotatable member that enters the magazine having a longitudinally curved card-supporting surface, longitudinally curved fingers projecting from the end of said curved card-supporting surface and upstanding ribs on the edges of said fingers.

7. In a card shuffling device, a card-receiving magazine, a member mounted for rotation on the side of said magazine and adapted when rotated to move into or out of said magazine, that portion of said rotatable member that enters the magazine having a longitudinally curved card-supporting surface and means on the end of the curved card-supporting surface for permitting separate cards from the supported pack to drop by gravity from different points in said pack until all of the supported cards have been released.

8. In a card shuffling device, a card receiving magazine, an arcuate member mounted for rotation on the side of the magazine and adapted, when rotated, to move into or out of said magazine, the longitudinally curved circumferential face of said arcuate member, providing a support for a deck of cards in said magazine, automatically operating means for actuating said supporting means to withdraw the same from the magazine, means for controlling the speed of operation of said card supporting actuating means and manually operable means for rotating said arcuate member so as to move the same into said magazine.

9. In a card shuffling device, the combination with means for holding a pack of cards, of rotary means mounted for rotation on the side of said card holding means and having a longitudinally curved slotted peripheral card supporting surface for permitting separate cards to drop by gravity from different points of the supported pack until all of the cards have been released from the card holding means, and automatically actuating means for timing the withdrawal movement of said rotary means.

10. In a card shuffling device, a magazine for the reception of a pack of cards to be shuffled, a rotary member mounted for rotation on the side of said magazine so as to move into and out of said magazine and supporting the pack of cards when moved into said magazine, and that portion of the periphery of said rotary member that projects into the magazine being curved lengthwise and provided with a pair of oppositely inclined side edges.

11. In a card shuffling device, a magazine, a curved rotary member mounted for rotation on the side of said magazine and adapted when rotated to move into and out of the lower portion of said magazine, said member having a curved circumferential surface which when moved into the magazine is adapted to support a pack of cards, that end of the member that enters the magazine being provided with edges that are inclined with respect to the arcuate line of travel of said member as it is withdrawn from said magazine, and automatically operating means for withdrawing said rotary member from said magazine.

12. In a card shuffling device, a housing provided in its upper portion with a magazine adapt-

- ed to receive a pack of cards and in its lower portion with a pocket, a rotary member mounted for operation on said housing and having a curved card supporting surface that is adapted to move into and out of the lower portion of said magazine as said member is rotated, the curved end of said member that enters said magazine being provided with inclined side edges, means for moving said member into said magazine, and means for withdrawing said member from said magazine.
13. In a card shuffling device, a magazine, a curved member mounted for rotation on the side

of the magazine and adapted when rotated to move into and out of said magazine, which curved member is provided with a longitudinally curved peripheral surface adapted to support cards when moved into said magazine, and means on the curved peripheral surface of said member for dividing the supported cards into a plurality of groups each comprising a plurality of cards and then permitting the cards to drop one at a time from each group as said card supporting member is rotated and withdrawn from the magazine. 5 10

HARRY E. McCOY.
